Attorney

UNITED STATES PATENT OFFICE.

ABBIE C. SPRAGUE, OF BOSTON, MASSACHUSETTS.

BOOKMARKER.

1,346,856.

Specification of Letters Patent.

Patented July 20, 1920.

Application filed February 14, 1920. Serial No. 358,588.

To all whom it may concern:

Be it known that I, ABBIE C. SPRAGUE, a citizen of the United States, and a resident of Boston, county of Suffolk, and State of Massachusetts, have invented an Improvement in Bookmarkers, of which the following description, in connection with the accompanying drawings, is a specification, like characters on the drawings representing like parts.

This invention relates to book-markers, and more particularly to means for marking a plurality of pages of a book in such a manner that they may be readily referred to in a predetermined order irrespective of the position of the various pages in the book to be referred to.

It is very often desirable to read certain passages or selections located in different portions of a book, in the order in which they are referred to in some other book, note or memorandum, but if the reader has to divert his attention from what he is reading to look up the next selection to be read, the reading is less satisfactory than it would be if the interruption had been avoided. It is therefore desirable, before starting to read any of the several selections, to mark the same so that they may be easily and quickly found in the order they are to be read.

The marking of the pages of a book for this purpose is comparatively easy if the selections to be referred to in a predetermined order are found upon the pages in the order in which the latter are arranged between the covers of the book, for in this case, all that is necessary is to insert pieces of paper or other markers between the pages of the book and then read the passages in the order these markers are arranged, from one cover of the book to the other. But if the passages to be referred to are not found in the order just mentioned, it is much more difficult to satisfactorily indicate the order in which the same are to be read; for example, if a page contains a passage which is to be read after the passages upon pages spaced upon opposite sides of the same are read, this order of reading cannot be indicated by merely inserting markers between the pages of the book.

The primary object of the present invention, therefore, is to provide a very satisfac-

tory book marker which may be easily and quickly arranged to indicate the location of the various passages to be referred to, and the order in which the same are to be read, irrespective of the location of the same within the book. A more specific object of the invention is to provide a book marker consisting of ribbons or other markers insertable between the pages of a book, and to provide an end of these markers with means for holding the same adjacent each other in the order in which the selections indicated thereby are to be referred to. The markers are made of flexible material in order that, when necessary, one may be crossed over the other so that the ends of the same may be held in the order the selections are to be read, irrespective of the portion of the book in which each selection to be read is located.

The above and other features of the invention and novel combinations of parts will be best made clear from the following description and accompanying drawing of a good practical form of the invention and its various novel characteristics.

In the drawing:

Figure 1 is a perspective view of a book showing the application of my invention thereto; and

Fig. 2 is a front view of the means for removably securing my marker to a book.

In Fig. 1 of the drawing is shown a book of the usual or any preferred construction and provided with backs or covers 10 and 11. This book is shown as held in an open position by one hand 12, and the other hand 13 is shown in the act of opening the book to a portion of the same next to be referred to, as indicated by one of the markers.

In the embodiment of my invention shown, I have illustrated a plurality of ribbons or markers designated as 14, 15, 16 and 17 adapted to be inserted between the pages of a book to readily designate the different pages to be referred to. In order that the pages that are thus marked may be readily referred to in a predetermined order, I have provided a headed pin or the like, 18, adapted to have the free ends of the ribbons removably secured thereto. In the particular device illustrated I have shown each of the ribbons as provided with a washer 14', 15', 16' and 17' preferably constructed of soft flexible material, such as leather; and these

washers are adapted to be threaded upon the pin 18, as clearly shown in Fig. 1. The pin 18 is preferably provided with a relatively large head 19 formed at one end thereof in order that the washers upon the free end of the ribbons may be threaded upon the pin 18 from only one end of the same. In order to prevent the washers after they have been threaded upon the pin 18 from becoming accidentally disengaged from the same, I have shown the forward end of this pin as provided with an enlargement such as 20, which is sufficiently large to fit snugly within the hole 21 formed through each of the washers. However, it will be apparent that various other means may be provided for preventing these washers from becoming accidentally disengaged from the free end of the pin 18.

In most applications of my invention it will be found desirable to provide means for removably securing my book-marker to the book upon which the same is to be used, although this is not an essential feature of my invention, and for this purpose I have provided the clips 22 and 23 (see particularly Fig. 2) one of which is adapted to be removably secured to the back or cover 10, while the other is to be removably secured to the back or cover 11. These clips 22 and 23 are preferably connected by a flexible member, such, for example, as a spring 24, to which the ribbons may be tied, as shown in the drawing. Each of the clips illustrated consists of a skeleton-like frame constructed of resilient metal and provided with a finger 25 formed integral therewith and projecting from a marginal portion of the frame into the skeleton-like structure, as clearly shown in Fig. 2.

In the use of my invention, the book-marker is preferably attached to the back of the book by means of the clips 22 and 23, as shown, then as soon as the various passages to be referred to in this book have been determined from some other book, one of the markers or ribbons 17 is placed between the pages to mark the last passage to be referred to in the anticipated reading, and the washer 17' of this ribbon is threaded upon the pin 18, then the next to the last passage to be referred to in reading the same book is designated by the marker 16, and the washer 16' upon this marker is threaded upon the pin 18. Then the third from the last passage to be referred to is similarly marked by the marker 15 and its washer 15' is threaded upon the pin, and finally the first passage to be referred to in reading this book is designated by the marker 14 and its washer 14' is the last to be threaded upon the pin, so that in starting out to read these various passages in accordance with the predetermined order, the first washer 14' is disengaged from its pins and as soon as the

page designated thereby has been found, this marker may be thrown back of the book out of the way, and as soon as this passage has been read, the washer 15' which designates the passage next to be read, is disengaged from its pin and thrown back out of the way as soon as the book has been opened to this second passage. In this manner it will be seen that the various passages to be read may be readily located in accordance with the predetermined order by simply disengaging a washer from the pin as each new place designated in the book is found.

From the foregoing remarks it will be seen that the passage in the book last to be referred to is the first to be marked in preparing for the anticipated reading and the first passage to be read is the one last marked by the ribbon, so that these passages are readily located in the desired order by simply removing a washer from the pin as each passage has been read. In other words, the washers are placed upon the pin in the inverse order in which the passages designated by the same are to be read.

It should be noted that the above described book marker enables one to readily locate the various pages of a book in a predetermined order irrespective of the location of the same in the book, and that this is due to the fact that each washer may be arranged upon the pin 18 in a desired order irrespective of whether the page marked by the same is near the back or the front of the book. In other words, if the first passage to be referred to should be near the front of the book and the second near the back of the book while a third passage lies in a portion of the book in between the first and second passages, the washers upon the ribbons marking the passages may be properly arranged upon the pin by crossing one ribbon over the other so that the washer first disengaged from the pin will mark the passage near the front of the book, and the next will mark the passage near the back of the book, and a third washer will indicate the position of the intermediate passage.

It will be apparent that various changes may be made in the device herein disclosed without departing from the spirit of my invention as defined in the annexed claims.

Claims:

1. A book marker comprising a plurality of ribbons adapted to be inserted between the pages of a book, said ribbons provided with means secured thereto, and a pin constructed to have said means removably arranged thereon in such a manner that they may be disengaged from said pin in the order in which the pages marked by said ribbons are to be referred to, said means upon the ribbons arranged to permit a portion of one ribbon between the same and

the book to be crossed over another ribbon in arranging the means in the desired order upon said pin.

2. A book marker for marking several pages of a book and indicating the order in which the same are to be referred to, comprising a plurality of ribbons insertible between the pages of a book, said ribbons provided with washers secured thereto in position to permit the portion of each ribbon between its washer and the book to be crossed over an adjacent ribbon in arranging the washers in the order the pages of the book are to be referred to, and a pin constructed 10 to have said washers arranged thereon in the order in which the pages marked by the ribbons are to be referred to.

3. A book marker for marking pages of a book and designating the order in which the same are to be referred to, comprising a plurality of flexible markers adapted to be inserted between the pages of a book, pin-engaging means upon end of said markers and positioned to permit the portion of said 20 markers between said means and the book to be crossed over an adjacent marker in arranging the washers in the order the pages of the book are to be referred to, and a pin constructed to have said means arranged 25 thereon in the order in which the pages marked are to be referred to.

4. A book marker, comprising a plurality of markers adapted to be inserted between the pages of a book, means for holding the 30 ends of said markers in such an arrangement that they may be disengaged from said means only in the order in which the pages marked by said markers are to be referred to, said markers constructed of flexible material to permit one to be crossed over the 35 other in arranging the ends of the same in the desired order upon said holding means.

5. A book marker comprising a plurality of ribbons or the like adapted to be inserted

between the pages of a book, said ribbons 45 provided with washers secured to an end thereof, and a pin constructed to have said washers arranged thereon in a manner to permit their removal therefrom only in the order in which the pages marked by said 50 ribbons are to be referred to.

6. A book marker comprising a plurality of ribbons adapted to be inserted between the pages of a book, a headed pin, said ribbons provided with means constructed to be 55 threaded upon said pin while the ribbon upon which the same is provided is in its marking position between the pages of a book, said pin provided with means for preventing the pin-engaging means from accidentally escaping from its end.

7. In a book marker a plurality of connected, fabricated markers adapted to be inserted between the pages of a book with free flexible end portions extending from between the pages thereof, said end portions constructed to permit one to be crossed over the other in arranging the same in the order in which the pages of the book are to be referred to, and means for holding said end 65 portions adjacent each other and in said order.

8. In a book marker, a plurality of ribbons adapted to be inserted between the pages of a book, means for removably securing said ribbons to a book, a headed pin, and flexible washers secured to the free end of said ribbons to be threaded upon said pin in the inverse order that the pages marked by said ribbons are to be referred to, said 75 pin provided with an enlargement remote from its head to prevent said washers from becoming accidentally disengaged therefrom.

In testimony whereof I have signed my 85 name to this specification.

ABBIE C. SPRAGUE.
